OF ILLINOIS.

STOP AND CHECK VALVE.

957,311.

Specification of Letters Patent.

Patented May 10, 1910.

Application filed November 7, 1908. Serial No. 461,475.

To all whom it may concern:

Be it known that we, GEORGE C. DAVIS and WALTER A. DALEY, citizens of the United States, residing at Chicago, in the county of Cook and State of Illinois, have invented a certain new and useful Improvement in Stop and Check Valves, of which the following is a specification.

Our invention relates to stop and check valves, such as are adapted for use in connection with separate steam boilers where they are connected in batteries, and the purpose of the stop and check valve is to control the steam passage between the separate boiler and its connection with the header.

Our invention is illustrated in the accompanying drawing, wherein—

Figure 1 is side elevation of parts of a boiler and header connection, with a vertical section through our valve; Fig. 2 is a cross section on line 2—2 of Fig. 1.

Like parts are indicated by the same letter in all the figures.

25 A is the individual boiler; A¹, the steam pipe leading thence to the valve; A², the pipe leading from the valve to the steam header A³ into which all the boilers are connected, and from which the steam supply is taken.

B is a pilot valve; B¹ the pipe leading thence to the boiler A; B² the pipe leading thence to our valve, and B³ the pipe leading from the pilot valve to the steam header.

35 C is the body of our stop valve, having the end C¹ to which the pipe A¹ is attached, and the end C² to which the pipe A² is attached. It also has the diaphragm C³ in which is placed the seat bushing C⁴ to receive the valve C⁵ on the stem C⁶.

C⁷ is the cover of the valve secured in position by the bolts C⁸. From this cover rise the two side members of the yoke, D D. They are connected above by the cross yoke

45 piece or head D¹. Laterally projecting from the side members of this yoke are the lugs D² D², in which is journaled the shaft E. The shaft carries at its outer end, the arm E¹ on which is adjustably mounted the weight E².

50 In the middle of the shaft is secured the sleeve E³ having the arms E⁴ E⁴ from each of which projects inwardly a finger E⁵. These fingers are received into the annular groove E⁶ in a projection F attached to the bottom of the cup

F¹, and screw-threaded at F² to the stem C⁶. This cup is filled with oil F³ to serve as a dash pot. In this form of the device the cup itself is movable, and its piston F⁴ is fixed as indicated. The piston may assume 60 any desired shape, but is preferably provided with pockets F⁵, perforated at their lower ends at F⁶, so as to open into the cup F¹ or oil chamber F³. The pipe B² opens into one or more of these air chambers F⁵ 65 as indicated at F⁷. The piston is held in position by the screw rods G G which take into its upper portion, and are held adjustably in position by the nuts G¹ G¹. On the top of these rods is placed the bar G² 70 held in position by the nuts G³ G³ and bearing upon the stuffing box cap G⁴ to close the stuffing box chamber G⁵, through which moves the shaft G⁶. This shaft has the hand wheel G⁷, screw threaded at G⁸ into the 75 piston, and has the projecting end G⁹ adapted when the hand wheel is operated to impinge upon the bottom of the cup, and thus enable the direct application of power to the cup to close the valve.

80 The pilot valve B consists of the casing and the balanced valve B⁴ on the stem B⁵ attached to the diaphragm B⁶ in the chamber B⁸ into which the pipe B³ opens. The arrangement is such as to keep the valve 85 shut between the boiler A and the chamber F³ when the pressures in the boiler and header are the same, and to open up the connection between the pipes B¹ and B² when the pressure in the header A³ becomes less 90 than the pressure in the boiler A. Any structure which will accomplish this result we call a pilot valve.

95 It is obvious that various changes can be made in the form and construction of our device without departing from the spirit of our invention. If protection is to be had only against breakages in the boiler, then the pilot valve and its associated parts are unnecessary. In that case also the piston 100 fitted into the oil cup could be movable. When the steam pipe B² is to be connected with the chamber in such piston, then the piston must be fixed as shown in our drawing.

105 F⁸ is a screw whereby the effective size of the opening F⁶ may be varied. The size and weight of the dash-pot portions and associated parts is of course a variable quantity and may be greater or less in propor- 110

tion to the cross sectional area of the rod C⁶. The weighted arm E¹ is adjustably secured as indicated by a set screw to the shaft E so that it can be extended in either direction.

The use and operation of our invention are as follows:—Assuming the parts to be in the positions indicated, and all properly connected, if the steam is generated in the boiler A, it tends to flow through pipe A¹, and through the valve into the header A³ lifting the valve C⁵ for that purpose. The changes in the situation may cause the valve to fluctuate but the dash pot effect prevents hammering or abrupt movement of the valve. If now the boiler breaks or leaks or its steam supply becomes inadequate, there is a tendency for the steam in the header, generated by the other boilers in the battery, to rush out into the damaged boiler. To do this however it must pass the valve C⁵. This valve the flow of steam will easily close, provided it is suitably balanced, but obviously there is a steam pressure upwardly on the bottom of the valve for a space equal in cross section to the cross section of the stem C⁶ which is not balanced, but which is exposed at the other end only to the air pressure. The current of the steam therefore tends on the one hand to close the valve and on the other to supply a pressure below the valve to keep it open. The cup on the dash pot structure attached to the top of the valve is balanced by the weight E². This weight is adjustable along the arm and is to be set at a point in proper relation to the normal pressure in the header A³, and its adjustment will also depend upon the area of the cross section of the stem C⁶. When properly adjusted the valve is balanced so that the tendency of the steam to keep the valve open is overcome. The flow of the steam therefore from the header A³ to the defective boiler A closes the valve C⁵ and maintains this condition until steam of a predetermined pressure is again generated in the boiler A. On the other hand, if a defect arises in the header A³ or some boiler connected with it, or if some boiler or pipe bursts, the pressure in the header A³ will be reduced, whereupon the diaphragm B⁸ being freed from the pressure on its upper side is moved upwardly and the balance valve is operated to open the connection between pipes B¹ and B² and allow the steam pressure in the boiler A to be transferred through pipe B² to the annular chamber F⁵ in the piston. This pressure applied to the top of the oil in that chamber, forces the cup or body of the valve with the stem C⁶ downwardly to seat the valve C⁵ on its valve seat and stop the flow from pipe A¹ through the valve into the header A³.

It will be observed that in connection with our check valve we employ an exterior dash-

pot and in connection with the movable part of the dash pot we employ a balancing apparatus to compensate for the steam pressure on the cross sectional area of the stem. Our balancing device is adjustable to accommodate this balance to various predetermined pressure limits in the header. It will also be observed that the piston is normally stationary and the cup movable and that in the form of our device here shown the hand wheel stem passes through the stationary piston so as to impinge upon the movable part of the dash pot and positively seat the valve when desired. These parts are all supported on the yoke which rises from the top of the check valve.

The boiler A we call the first source of steam supply, and the header A³ the second source of steam supply. There are two steam connections between them; one, with in which the check valve is located, the other within which the pilot valve is located. As previously explained this pilot valve operates to turn the pressure of the first source of steam supply into the dash-pot chamber 90 when there is an abnormal reduction of the pressure in the header. Since the area of the movable part of the dash-pot is greater than the effective area of the valve C⁵ this action will positively seat the valve C⁵. On the other hand, if there is an abnormal reduction of pressure in the boiler A of the first source of supply, the pressure on the boiler side of the valve C⁵ will be a trifle less than on the other side, but not sufficient to close 100 the valve because though the pressure is lower it has the advantage of working outwardly against an area equal to the cross sectional area of the stem C⁶ against air pressure. It is to compensate for this inequality or balance it that we employ our balancing device or rock shaft and weighted arm.

As heretofore described, the weight is adapted to balance the pressure incident to 110 the cross sectional area of the rod C⁶, but if, as previously explained, the dash-pot portions were made sufficiently heavy they would balance the pressure due to the cross sectional area of the rod C⁶ or there might 115 be other arrangements so as to get rid of the effect of the cross sectional area of that rod either temporarily or for certain conditions of variation of the pressure in the header. The weight, therefore, by shifting 120 its position on the arm and by shifting the position of the arm on the rod may be made to balance or compensate for any such inequality at any given pressure in the header. It may balance the pressure due to the cross 125 sectional area of the rod C⁶ or it may balance the inequality in weight between the dash-pot portions and the valve. In short, the weight device is a balancing device to compensate either for the steam pressure on 130

the cross sectional area of the dash-pot stem or the inequality in the weights of the moving portions or either.

I claim:

- 5 1. In a stop and check valve for controlling a steam passage, the combination of a valve with an exterior dash-pot removed from the influence of the steam associated therewith to regulate its action.
- 10 2. In a stop and check valve for controlling a steam passage, the combination of a valve with an exterior dash-pot removed from the influence of the steam associated therewith to regulate its action, and a balancing device to compensate for the steam pressure on the cross sectional area of such dash-pot stem.
- 15 3. In a stop and check valve for controlling a steam passage, the combination of a valve with an exterior dash-pot removed from the influence of the steam associated therewith to regulate its action, and a balancing device to compensate for the steam pressure on the cross sectional area of such dash-pot stem, said balancing device adjustable to accommodate for predetermined pressures in the steam header.
- 20 4. In a stop and check valve for controlling a steam passage, the combination of a valve with an exterior dash-pot removed from the influence of the steam associated therewith to regulate its action, and a balancing device to compensate for the steam pressure on the cross sectional area of such dash-pot stem, such balancing device consisting of a rock shaft associated with the movable part of the dash-pot and a weighted arm projecting therefrom.
- 25 5. In a stop and check valve for controlling a steam passage, the combination of a valve with an exterior dash-pot removed from the influence of the steam associated therewith to regulate its action, and a balancing device to compensate for the steam pressure on the cross sectional area of such dash-pot stem, said balancing device adjustable to accommodate for predetermined pressures in the steam header, such balancing device consisting of a rock shaft associated with the movable part of the dash-pot and a weighted arm projecting therefrom.
- 30 6. In a stop and check valve for controlling a steam passage, the combination of a valve with a dash-pot whose movable part is connected with the valve, a balancing device connected with such movable part and adapted to compensate for the pressure on the cross sectional area of the dash-pot stem.
- 35 7. In a stop and check valve for controlling a steam passage, the combination of a valve with a dash-pot whose movable part is connected with the valve, a balancing device connected with such movable part and adapted to compensate for the pressure on the cross sectional area of the stem, and a three-

way pilot valve with connections on both sides of the main valve and another to the dash-pot.

8. A stop and check valve comprising a valve, a stem, a dash-pot having a movable inclosing cylinder attached to said stem, a rock shaft, connections thence to the movable portion of the stem, and a weighted arm on the rock shaft.

9. A stop and check valve comprising a valve, a stem, a dash-pot having a movable inclosing cylinder attached to said stem, a rock shaft, connections thence to the movable portion of the stem, a weighted arm on the rock shaft, and a normally fixed piston for such dash-pot.

10. A stop and check valve comprising a valve, a stem, a dash-pot having a movable portion attached to said stem, a rock shaft, connections thence to the movable portion of the stem, a weighted arm on the rock shaft, a fixed piston for such dash-pot, and a hand wheel and stem which passes through the piston and abuts the movable portion of the dash-pot.

11. A device for controlling the steam connection between two sources of supply comprising a connecting pipe between the two sources, a stop and check valve in such pipe, a stem leading from the valve, a dash-pot to regulate the action of the stem, a second steam connection between the two sources, a pilot valve, and a connection thence to the dash pot.

12. A device for controlling the steam connection between two sources of supply comprising a connecting pipe between the two sources, a stop and check valve in such pipe, a stem leading from the valve, a dash-pot to regulate the action of the stem, a second steam connection between the two sources, a pilot valve, and a connection thence to the dash-pot, said pilot valve adapted to connect the chamber of the dash-pot with the first source of supply when the pressure in the second source of supply is abnormally reduced.

13. A device for controlling the steam connection between two sources of supply comprising a connecting pipe between the two sources, a stop and check valve in such pipe, a stem leading from the valve, a dash-pot to regulate the action of the stem, a second steam connection between the two sources, a pilot valve, and a connection thence to the dash-pot, said dash pot having a movable part connected to the stem of the valve, and a balancing device associated therewith to compensate for the pressure on the cross sectional area of the valve stem.

14. A device for controlling the steam connection between two sources of supply comprising a connecting pipe between the two sources, a stop and check valve in such pipe, a stem leading from the valve, a dash-pot

to regulate the action of the stem, a second steam connection between the two sources, a pilot valve, a connection thence to the dash-pot, said dash-pot having a movable part 5 connected to the stem of the valve, and a balancing device associated therewith to compensate for the pressure on the cross sectional area of the valve stem, said balancing device adjustable to adapt it to varying 10 pressures on the source of steam supply.

15. In a stop and check valve for controlling a steam passage, the combination of a valve with an exterior dash-pot associated therewith to regulate its action, and a balancing device to compensate for the inequalities 20 between the valve and the movable portion of the dash-pot.

16. In a stop and check valve for controlling a steam passage, the combination of a 25 valve with an exterior two-chamber dash-pot removed from the influence of the steam associated therewith to regulate its action, and means for regulating the flow of fluid from one chamber to the other.

25. 17. In a stop and check valve for controlling a steam passage, the combination of a valve disk with an exterior dash-pot removed from the influence of the steam associated therewith to regulate its action, a 30 stem connecting said dash-pot and disk, and means for balancing the steam pressure on the cross sectional area of the stem.

18. In a stop and check valve for controlling a steam passage, the combination of a 35 valve disk with an exterior dash-pot removed from the influence of the steam associated therewith to regulate its action, and means to compensate for the weight of the moving part less the pressure on the cross 40 sectional area of such dash pot stem.

19. In a stop and check valve for controlling a steam passage, the combination of a valve with an exterior dash-pot removed from the influence of the steam associated 45 therewith to regulate its action, a connection between the valve and the moving portion of the dash-pot, and a balancing device associated with such movable part of the dash-pot.

50. 20. In a stop and check valve for control-

ling a steam passage, the combination of a valve with an exterior dash-pot removed from the influence of the steam associated therewith to regulate its action, a connection between the valve and the moving portion 55 of the dash-pot, and a balancing device associated with such movable part of the dash-pot consisting of an adjustable weight.

21. In a stop and check valve for controlling a steam passage, the combination of a 60 valve with an exterior dash-pot removed from the influence of the steam associated therewith to regulate its action, a connection between the valve and the moving portion of the dash-pot, and a balancing device associated with such movable part of the dash-pot consisting of a weight adjustable to vary 65 its effective power and the direction of its pull.

22. A stop and check valve comprising a 70 valve, a stem, a dash-pot having a movable portion attached to said stem, a rock shaft, connections thence to the movable portion of the stem, a weighted arm on the rock shaft and a normally fixed piston and a movable 75 cylinder for such dash-pot.

23. A stop and check valve comprising a valve, a stem, a dash-pot having a movable inclosing cylinder attached to said stem, a rock shaft, connections thence to the movable portion of the stem, a weighted arm on the rock shaft, and means for adjusting the 80 resistance to the movement in the dash-pot.

24. A stop and check valve comprising a valve, a stem, a dash-pot having a movable 85 portion attached to said stem, a rock shaft, connections thence to the movable portion of the stem, a weighted arm on the rock shaft, and means for adjusting the resistance to the movement in the dash-pot, said means containing a normally fixed piston, a movable 90 cylinder, a chamber in said piston, an opening from the dash pot chamber into said chamber, and means for regulating the size of said opening.
